CLAIM

The ornamental design for a terminal fitting for a tubular conduit, substantially as shown and described.

DESCRIPTION

FIG. 1 is a top plan view of a terminal fitting for a tubular conduit showing my new design;

FIG. 2 is a side elevational view thereof;

FIG. 3 is an elevational view taken from one end thereof; and

FIG. 4 is an elevational view taken from the end opposite that shown in FIG. 3.

The fragmentary broken line showing of a tubular conduit in FIG. 1 is for purposes of illustration only.
